UNITED STATES PATENT OFFICE.

HARRIS F. POMEROY, OF FLINT, MICHIGAN.

MECHANICAL POWER TRANSMISSION.

1,315,985.

Specification of Letters Patent. Patented Sept. 16, 1919.

Application filed March 18, 1919. Serial No. 282,435.

To all whom it may concern:

Be it known that I, HARRIS F. POMEROY, a citizen of the United States, residing at Flint, county of Genesee, and State of Michigan, have invented a new and useful Improvement in Mechanical Power Transmissions, of which the following is a specification.

This invention relates to power transmission lines of the mechanical type. Its object is to transmit reciprocating motion over convenient distances so as to operate various machinery. It is more particularly adapted for the transmission of light power to the various machinery on a farm.

In farm work it is often found that various devices and machines needing power must be located at relatively remote points. For instance, it may be desirable to have power to drive the dairy machinery. It is also necessary to have some kind of power to pump water. Very often a pump is located at a different point from the dairy. Or for that matter, the owner may desire to have his internal combustion engine in the cellar, where it will not freeze in winter. He may wish to transmit power to his dairy machinery or to his pump and this, of course, will be outside of the cellar. It is found that ordinary belting is very unsuitable for this purpose and is also dangerous passing near the ground in an unprotected position. It is the object of this invention to provide a very simple power transmission line equipped with the devices necessary to make it a practical success.

In the drawings,—

Figure 1 is a view in general outline of the transmission line showing it coupled up with a pump and a gas engine motor.

Fig. 2 is a perspective showing the double bell crank rocker at the power end of the line.

Fig. 3 is an elevation of the bell crank rocker at the work end of the transmission line, taken from the right of the showing of the pump in Fig. 1.

Fig. 4 is a center cross section through the tightening reel used on one end of the cable.

Fig. 5 is a side elevation of one of the intermediate supports for the cables.

Fig. 6 is another side elevation of the same taken in a 90 degree position from the showing in Fig. 5.

Fig. 7 is a detail of cable fastenings at the work end of the transmission line.

Fig. 8 is a side elevation of the spacer used to space the cables.

M designates the motor, which may be an electric motor or an internal combustion engine. This can be used in the engine house, dairy or other place to drive other machinery, such as shafting *a*, for example. This motor drives a connecting rod *b*, which rocks the rock arm *c*, which is part of the double bell crank rocker and is supported in the bearing *d* on the post *e*. This bell crank rocker comprises the crank arm *c* which has an elbow connection with the shaft *f* that passes through the bearing and on to the squared end of which is fastened the rock arm *g*. Through the ends of the rock arm *g* are threaded the hook bolts *h*, upon which hooks the clevis *i* of a cable tightener and reel. This comprises simply a spool journaled in the ends of the clevis. These reels are supported on small shafts *j* that run through the ends of the clevis and terminate in squared ends *l* which are suitable for the application of a wrench to turn the spool to tighten the cable or loosen the cable. A large gravity pawl *k* engages in the ratchet teeth *m* on the ends of the spool to hold the reel in any given position of adjustment.

These cables (preferably wire) are intended for relatively long distances of 50, 100 feet, or more, and it is advisable to have intermediate supporting posts *n* on which are supported rotatably the grooved rolls *o* over which the cable may be run as a support. These cables would objectionably lash back and forth and vibrate up and down were it not for the spacing frames that I provide between the supports. This not only prevents the lower cable from drawing away from the upper cable but also prevents it from approaching the upper cable. These spacers are designated *p* in Fig. 1, and are detailed in Fig. 8, which is a view looking edgewise at the spacer. It will be found that it comprises two vertical pieces of strap iron connected at the top by a flat piece of strap iron which is secured to the two vertical runs of strap iron by the hook bolts *q* which also pinch the cable *r* tightly to the top of the spacing frame. On the lower end of the spacer hook bolts *s* support a tube *t* through which the cable *u* runs freely. Hence the upper cable is rigidly fastened to the spacer and the lower cable runs through the tubing in the spacer, which serves to accurately keep the oppo-

sitely traveling cables in properly spaced relation. The amount of spacing can be adjusted by moving the bolts *s* along to other holes *5* in the upright straps.

- 5 On the work end of the line is a three-arm bell crank lever, two of which are the power arms and the other the resistance arm. The power arms are in alinement and have hook bolts *v*, one bolt passing through each arm
10 to hook into a clevis *x* which rotatably supports the pulley *y* around which the cable is run and then clamped together by the clamp *z*. This enables a certain turning movement to take place due to the action of the bell
15 crank arm without wearing the cables, for the cable merely turns with the pulley as the pulley accommodates itself to the bell crank arm swinging through its arc.

It will be seen that the resistance arm and
20 the upper power arm of the double bell crank lever at the work end of the line are connected by a brace *1* to brace the same. The resistance arm of the double bell crank lever is shown attached to the pump rod *2* with which it may do work. This is only used for an illustration for obviously it can be used to do other work.

The bell crank arms are built of tubing united by suitable coupling so as to stand a
30 side draft, for the bearing cannot perhaps be so placed as to be exactly perpendicular to the line of draft.

What I claim is:

1. A mechanical power transmission, having in combination, a pair of rock arms supported to rock at points remote from each other, cables connecting the ends of one rock arm with the ends of the other rock arm, and a spacing frame comprising a member
35

rigidly connected with one cable and having 40 a tubular member that ensheathes the other cable and allows the cable to slide therethrough.

2. A mechanical power transmission, comprising a pair of rock arms supported to 45 rock at points remote from each other, cables connecting the ends of one rock arm with the ends of the other rock arm, and tightening devices for taking up slack in the cables, comprising spools about which the cables 50 wind and a ratchet and pawl.

3. A power transmission, having in combination, a pair of rock arms supported to rock at points remote from each other, cables connecting the ends of one rock arm with the 55 ends of the other rock arm, and a spacing frame comprising a rectangular frame having one of the upper or lower cross members adapted to move with the cable that it is secured to and the other member arranged 60 to slide on the cable which it engages.

4. A mechanical power transmission, having a pair of rock arms supported to rock at points remote from each other, cables connecting the ends of one rock arm and the 65 ends of the other rock arm, and a spacing frame comprising a rectangular frame having upper and lower cross members and two uprights, the uprights being perforated and one of the cross members adapted to be bolted at various points along the slots and one of the said cross members being attached to one cable to travel with it and the other cross member being attached to the other cable to slide upon it.

In witness whereof I have hereunto set my hand on the 5th day of March, 1919.

HARRIS F. POMEROY.
